UNITED STATES PATENT OFFICE

112,441

DESIGN FOR A DOLL

Francis Edward Weidhaas, Bronxville, N. Y.

Application June 2, 1938, Serial No. 77,504

Term of patent 7 years

To all whom it may concern:

Be it known that I, Francis Edward Weidhaas, a citizen of the United States, residing at Bronxville, in the county of Westchester and State of New York, have invented a new, original, and ornamental Design for a Doll, of which the following is a specification, reference being had to the accompanying drawing, forming part thereof.

I claim—

The ornamental design for a doll, substantially as shown.

FRANCIS EDWARD WEIDHAAS.
